DOOR-HOLD-OPEN DEVICE

John J. Muldoon, Roseville, Mich., assignor to
Ternstedt Manufacturing Company, Detroit,
Mich., a corporation of Michigan

Application April 2, 1942, Serial No. 437,394

4 Claims. (Cl. 16—142)

This invention relates to door-hold-open devices.

It is desirable with the doors of automobiles to have a positive means for holding the door in open position as the way some of the doors are now hung there is a tendency for some of them to swing toward the closed position and interfere with one getting in or out of the car. Various devices for this purpose have been proposed, such as links passing through the body post and arranged to be engaged by spring stressed devices, and in some cases means have been associated with the hinges of the door to form catches to hold the door temporarily in open position.

It is the object of the present invention to provide a new and novel device for this purpose which is associated with the hinge. It can be used either with the conventional concealed hinge having a goose-neck hinge arm or it can be used with a hinge having hinge butts concealed behind the door overlap flange.

In the drawings:

Fig. 1 is a horizontal fragmentary section through the body post and the door showing a hinge of the concealed type which is concealed behind the overlap flange. This hinge is equipped with my improved door-hold-open device.

Fig. 2 is a section on the line 2—2 of Fig. 1.

Fig. 3 is a plan view of a concealed hinge of the conventional type embodying my improvement.

Fig. 4 is a side elevation of the same.

Fig. 5 is a view of the body pillar showing this type of hinge secured thereto.

Referring to Fig. 1, 1 designates the hinge butt secured to the body pillar 2. 3 designates the hinge butt secured to the door pillar or door jamb 4. Hinge butt 3 has a pair of knuckle carrying arms 5 and 6 which straddle the knuckle carrying arm 7 of hinge butt 1. The knuckles on the ends of these arms are aligned and the hinge pin 8 passes through the opening in the knuckles. The knuckle carrying arm 5 is slotted as at 9 to receive a stiff, heavy wire spring that constitutes the door-hold-open device. This spring has down-turned arms 10 and 11 which fit into holes 12 and 13, respectively, drilled in the knuckle carrying arm 7 of the hinge butt attached to the body. The main portion of the door retaining spring lies in a horizontal plane and comprises a loop 14 provided with a restricted portion or throat 15. The upper knuckle carrying arm 5 of the door hinge butt is bored as at 16 and a hardened steel pin 17 is driven into this bore from the bottom. When the door swings open,

this pin passes along the opening in the loop, passes through the throat 15 which is slightly smaller than the diameter of the hardened pin. This spreads the legs of the loop and tends to hold the door in its open position or at least in an open position at approximately 57° of opening and the maximum opening is 73°.

It may be explained here that many of the doors are so hung that when the door is fully open the door does not tend to close because the natural swing of the door, after it passes a neutral point, is toward an open position. Hence, this particular design of hold-open device will prevent the door from swinging closed as it passes inwardly beyond that neutral point. I have found that the throat placed in a position to hold the door at substantially a 57° angle accomplishes this purpose in some installations. But with a door that rises at all points in the outward movement, a 57° opening or thereabouts, is an average opening movement by the average person and so it is desirable to have the device operative at about this degree of opening.

The hinge butts are secured to the door post or jamb and the body pillar in the customary way by screws which are here indicated only diagrammatically. A box or casing 18 may be welded to the back of the jamb strip 19 and to the L-strip 20 which in turn is welded to the back of the inner panel 21 and the jamb strip 4 of the door.

In the form of the invention shown in Figs. 3 to 5 inclusive, my door-hold-open device is applied to the box type of concealed hinge with the goose-neck arm. The hinge box is designated 22 and is formed by stamping a loop in the hinge plate 23 which is secured to the body pillar by screws 35. A facing plate 24 is spot welded to the outside of the hinge box at the points 36. This plate adds strength to the assembly by tying the upper and lower portions of the loop together. The goose-neck arm 25 is held in place by the knuckle pin 26. 28 is a spacing flange punched out of the top wall of the box and the arm is spaced from the floor of the box by a similar flange (not shown).

In this space is located my improved door-hold-open device which consists of a heavy, stiff wire spring having a loop formation. A loop 29 has a restricted portion or throat 30. There is another loop 31, between the throat 30 and the leg 32 which is turned down and passes through the floor of the hinge box to anchor the device in place. There is another leg 33 turned down and passing through an opening in the floor of the hinge box to anchor the other end of the

spring in place. The spring is, in its general formation, a double loop or S-shaped spring. The hardened steel pin 34 is driven into an opening in the bottom of the goose-neck arm and this hardened pin is arranged to pass through the throat 30 which is somewhat narrower than the diameter of the pin. When the pin passes through the throat, the door will be held from swinging closed at a point approximately 59° in its opening, while its maximum opening may be 79°. I do not wish to be in any way confined to the degrees of opening stated here or in connection with the other form of my invention. I merely refer to them as illustrative of the positions where the devices in these two installations are designed to hold the doors.

What I claim is:

1. A combined hinge and door-hold-open device, comprising a pair of hinge members secured together by a knuckle pin and arranged to have relative swinging movement with respect to each other, a spring member interposed in part between the hinge members and in the form of a loop with a restricted or throat portion, the said loop having its ends turned in and secured to one of the hinge members and a pin on the other hinge member larger in diameter than the opening in said throat portion and arranged to travel in side the said loop and spread the loop at the throat when the hinge members have relative movement through a given arc and thereby temporarily hold the door in an open position.

2. A combined hinge and door-hold-open device, comprising a pair of hinge members secured together by a knuckle pin and arranged to have relative swinging movement with respect to each other, a spring member in the form of a loop with a restricted or throat portion, the said loop

5 having bent-over legs secured to one of the hinge members and a pin on the other hinge member of larger diameter than the opening in the throat portion and arranged to travel inside the said loop and spread the loop at the throat when the hinge members have relative movement and thereby temporarily hold the door in an open position.

10 3. A combined hinge and door-hold-open device, comprising a pair of hinge members secured together by a knuckle pin and arranged to have relative swinging movement with respect to each other, a spring member in the form of a double loop of S-shape with a restricted or throat portion, the said spring secured to one of the hinge members and a pin on the other hinge member arranged to travel inside one of said loops and spread the loop at the throat when the hinge members have relative movement and thereby temporarily hold the door in an open position.

20 4. A combined hinge and door-hold-open device, comprising a pair of hinge members secured together by a knuckle pin and arranged to have relative swinging movement with respect to each other, a spring member interposed in part between the hinge members and in the form of a loop of heavy spring wire with a restricted or throat portion, the said loop having its ends secured to one of the hinge members and a pin on the other hinge member arranged to travel inside the said loop and spread both sides of the loop at the throat when the hinge members have relative movement through a given arc and thereby temporarily hold the door in an open position.

JOHN J. MULDOON.
